[57] **CLAIM**

The ornamental design for battery state-of-charge meter, as shown and described.

DESCRIPTION

FIG. 1 is a left front perspective view of a battery state-of-charge meter showing my new design with decorative front panel broken away for ease of illustration; FIG. 2 is a left side elevational view thereof, the broken-line showing an intermediately placed instrument panel, which is environmental only and forms no part of the claimed design;

FIG. 3 is a top plan view of FIG. 2;

FIG. 4 is a rear elevational view thereof;

FIG. 5 is a front elevational view thereof;

FIG. 6 is a left side elevational view thereof, the broken-line showing a surface mounted instrument panel which is environmental only and forms no part of the claimed design;

FIG. 7 is a bottom plan view of FIG. 6.

In FIGS. 1 and 5, per the diagonal lines indicates the color brown.
